poration of Delaware

Application December 31, 1943, Serial No. 516,323
In Great Britain February 10, 1943

9 Claims. (Cl. 179—22)

1

The present invention relates to telephone or like systems and is more particularly concerned with automatic telephone systems of the type disclosed in our application Serial No. 513,370, filed Dec. 8, 1943, in which the crossbar switch mechanisms provided at the various switching stages, viz., the group and penultimate selecting stages, have associated therewith control equipment adapted to receive the requisite dialled rigid or digits, and in response thereto to affect the setting up of the associated crossbar switch. Each crossbar switch can handle more than one connection and where two or more connections are to be set up through any one switch, the associated control equipment will be repeatedly utilised to enable these connections successively to be set up.

In the case of multi-exchange working a crossbar switch serving in an incoming group selecting capacity will terminate a number of junction lines corresponding to the number of connections which it can accommodate, and in these circumstances difficulties arise in ensuring that when the associated control equipment is handling the setting up of a connection from one incoming junction, the distant or originating ends of the other junction lines concerned shall be suitably informed.

The object of the invention is to enable these difficulties to be overcome in a simple and efficient manner.

According to the invention a crossbar selector unit adapted to serve a number of incoming junction lines and having a control circuit individual to the unit and adapted to control the selector unit to set up one call at a time from any junction line to an idle line in a group determined by the number of impulses in a series transmitted to said unit is so arranged that in order to prevent impulses being transmitted over two or more of said junction lines simultaneously, a signal circuit extends over each junction circuit from the crossbar selector unit by which signal circuit the control circuit is enabled to indicate when a junction line is in readiness for the transmission of impulses thereover. In one example impulse regenerators are provided at the outgoing end of each junction line which regenerators are adapted to store the impulses transmitted to the line when a signal is received from the control equipment.

In another example all the idle junction lines having access to a group selector unit are rendered unavailable while the control circuit is in use, that is, until an idle line in a desired group has been selected.

2

The invention will be better understood from the following description of two methods of carrying it into effect, reference being had to the accompanying drawings comprising Figs. 1-6. 5 Figs. 1-4 when arranged in the manner indicated in Fig. 4b (located at the foot of Fig. 4) show circuits of a crossbar group selecting unit and of its individual control equipment. The group selecting unit serves ten incoming junction lines, the arrangements being that only one junction line can switch through to the control equipment at a time and that sending out of impulses from the distant end is dependent upon the switching through of the line concerned to the control equipment. A trunking diagram of the unit is shown in Fig. 4a.

An alternative method of "busy" signalling is disclosed in Figs. 5 and 6, Fig. 5 showing the elements of an outgoing auto-to-auto impulse repeating relay set adapted to mark itself as busy 20 in response to a "junction busy" signal from the distant incoming end, while Fig. 6 shows the modifications which are necessary to the incoming crossbar group selecting unit of Figs. 1-4 to enable "junction busy" signalling to be carried out whenever the associated control equipment is in use.

In the circuit diagrams the number of contact units carried by each relay is shown underneath 30 its designation, as for instance

$\frac{1K}{3}$

Fig. 1, the contact units being designated individually in small letters which in this instance will be $1k1$, $1k2$ and $1k3$. A slow-to-release relay is shown with a hatched portion at one end of the rectangle indicative thereof, while a slow-to-operate relay is shown with a cross at one end, 40 such a relay being in some instances slow-to-release as well as slow-to-operate.

As regards the crossbar vertical and horizontal relays, these are each indicated by a hatched rectangle, the contact units individual thereto 45 being indicated in the same manner as for ordinary relays. The sets of crossbar switch contacts proper which are closed at the intersection of any given pair of horizontal and vertical bars, say controlled by relays $1GSP$ (Fig. 1) and $1GSH$ (Fig. 2), are designated

$1GSP\ 1, 1GSP\ 2$
 $1GSH\ \underline{1GSH}$

and so on for each set of contacts involved.

55 Of the various uni-selectors such as the con-

trol group digit switch which will be referred to as DS, the various sets of wipers and banks are designated DS1, DS2 etc. The driving magnet which is indicated by a hatched square will, in this instance, be designated DM, and the magnet interrupter contacts will be designated dm. In the case of the digit switch DS, since the number of positions required is considerably less than the twenty-five available, they are arranged to make two appearances on the banks thereof so that this switch will have two home positions, 1 and 12.

Referring now to the trunking diagram of Fig. 4a, the crossbar group selector unit will be hereafter referred to as a group selector, although in fact it serves as a number of group selectors in the accepted sense of the phrase. It preferably comprises two crossbar switching units with their vertical bars in effect coupled together as shown to form a group selector. More specifically, the coupling will be effected electrically by the connection of each column of vertically commoned contact springs of the spring sets in one unit with a corresponding column of vertically commoned contact springs on the other unit of the pair.

The selector is of the 10-level 20-outlet per level type and is capable of handling ten connections, and for this purpose ten incoming junctions from distant exchanges can be served thereby and will connect with the horizontal bar relays 1GSP-10GSP. The horizontal bars provided for the purpose of determining the selected one of the ten possible levels are controlled by the relays 1GTP-10GTP and the two sets of ten vertical hold relays 1GSH-20GSH and 1GTH-20GTH when operated in pairs such as 1GSH and 1GTH or 2GSH and 2GTH and so on and in conjunction with one incoming and one level selecting relay, enable the two units of the pair forming the group selector switch proper to function to connect an incoming junction line via a free internal link within the selector to a free one of the twenty outgoing external links accessible from a selected level of the selector and extending to a succeeding switching stage.

Referring now to the circuits of Figs. 1-4, circuits of the group selector which will be termed GSU are shown in the upper parts of Figs. 1 and 2, while circuits of the control group or equipment which will be termed GCG are shown in the lower parts of these figures and in Figs. 3 and 4.

In the group selector circuit there is shown the horizontal prepare relay 1GSP together with the auxiliary relays 1GSR, 1K and 1NF associated with the first out of the ten possible incoming junctions to the selector, which relays, in common with the corresponding relays of the nine other incoming junctions have access over common leads 10-14 to the control group GCG. For junction busying purposes, as will be later appreciated, the relays 1GSP-10GSP associated with the ten incoming junctions are arranged in a chain switching circuit, of which relays 1GSP, 2GSP and 10GSP are shown. In addition, the vertical hold relays 1GSH and 1GTH of the first vertical internal link and horizontal prepare relay 1GTP associated with the first of the ten possible outgoing levels are also shown.

The control group GCG comprises a set of relays and three uniselectors of the 25-point reverse-drive electromagnetically operated type, the received dialled group selecting digit being received on switch DS, whereupon the corresponding one of the level selecting relays 1GTP-10GTP

is operated. One or other of the outlet control switches AOS or BOS, according to whether digits 1-5 or 6-0 are dialled, is then caused to test over the twenty outlets of the selected outgoing level, and in accordance with the particular outgoing outlet taken into use a particular one of the twenty pairs of vertical hold relays is operated to switch the connection through and the control group is then released for further use in piloting a subsequent call through the same group selector.

Considering now the taking into use of the group selector, there will be provided at the outgoing originating end of each of the junctions a relay set provided with impulse storage and re-transmission facilities, the re-transmission being adapted to be initiated only in response to a signal from the distant incoming end of the junction line. Such a relay set is disclosed in Figs. 4 and 5 of United States Patent No. 2,154,776, granted April 18, 1939.

On the seizure of this relay set via a preceding selector train, an earth potential is extended forward over the negative junction wire, while a battery potential via the winding of a relay is extended forward over the positive junction wire.

At the incoming end of the junction the negative lead connects with the relevant horizontal prepare relay, 1GSP in this instance, where the first one of the ten possible junction lines served by selector GSU is being considered. This relay is connected via contacts 1gsp2 and n3 and chain connected contacts 10gsp3-1gsp3 to battery via resistance YA. It will be noted that there is no standing earth connection to the positive line so that the relay in the outgoing relay set cannot yet operate. At the group selector end of the junction, if no other call is in process of being set upon selector GSU, none of the relays 2GSP-10GSP will be operated, and relay 1GSP can therefore operate and at its make-first light contacts 1gsp1 completes a local locking circuit for itself, whereupon it actuates its associated horizontal bar. At contacts 1gsp2 any back feeding circuit for the YA resistance battery to the other line relays is disconnected, while at contacts 1gsp3 any operating circuit for these other relays is further disconnected. Relay 1GSP also in operating connects the calling incoming junction through to common equipment GCG in the following manner. At contacts 1gsp7 (Fig. 2) the earthed winding of the impulse responding relay A is connected up to the positive line and at contacts 1gsp6 an earth is extended downwardly to operate relay A on its left-hand winding.

The connection of relay A to the positive line enables the waiting relay at the outgoing end to operate, and when it does so, the outgoing relay set is conditioned for sending out any trains of dialled impulses which it receives. Meanwhile, relay A in operating at contacts a1 (Fig. 3) operates relay B in series with rectifier MRA to battery via resistance YG. Relay B in operating at contacts b1 provides an earth potential for the DM magnet impulsive circuit, at contacts b2 completes an energising circuit for relay C in series with resistance YH and magnet DM (non-operative in this condition), at contacts b4 (Fig. 1) extends to an earth on to common lead 10 so as to bring up relay 1GSR and at contacts b5 brings up relay BB. The group selector relay 1GSR in operating at contacts 1gsr1 disconnects relay 1GSP from the incoming negative lead and completes a local locking circuit therefor, while

at contacts $1g_{sr2}$ (Fig. 2) it extends the left-hand winding of relay A to the negative conductor and this relay now holds on both its windings to the loop extended forward from the distant outgoing relay set, and subsequently responds to the first train of impulses to be re-transmitted therefrom. Relay BB in operating at contacts $bb1$ connects the centre winding of relay TA to common lead S, its other contacts having no function at this stage. Relay C in operating at contacts $c1$ (Fig. 3) prepares for the reception of the group selecting digit on magnet DM of switch DS.

In case the calling party should neglect to dial the group selecting digit, the common equipment GCG will be held unnecessarily and relay $1GSP$ (Fig. 1) in remaining operated will prevent any of the other relays $2GSP-10GSP$ from being operated by calls received over any of the nine remaining incoming junctions to the group selector GSU, and so will prevent a call being set up from any of these sources. Arrangements are therefore made to release equipment GCG and to return a busy tone to the calling subscriber if the group selecting digit is not dialled within a predetermined period after seizure of the equipment GCG. The timing of this period is effected by the use of a pair of relays TA and TZ (Fig. 3) in conjunction with a delay set (not shown) which is common to the exchange and which is arranged to supply earth pulses bearing a definite time relation to common leads S and Z. On operation of relays B and BB when control group GCG is taken into use, contacts $bb1$ (Fig. 1) connect the centre winding of relay TA to the S lead and if the delay set is in its normal position, an earth will be encountered on this lead and relay TA will operate. At contacts $ta1$ it connects its left-hand winding and the lower winding of relay TZ to the Z lead, while at contacts $ta2$ it locks to earth over its right-hand winding. At contacts $ta3$ it extends earth on to the delay set start lead ST. After the predetermined period an earth pulse is applied from the delay set to the Z lead, whereupon relay TZ operates and at contacts $ta1$ removes the short-circuit from its upper winding over which it locks to the earthed contacts $b5$ via resistance YB. At contacts $ta2$ and $ta3$ the initial locking and operating circuits for relay TA are opened, but this relay remains held via the lower winding of relay TZ. At contacts $ta2$ earth is extended over common lead 14 to bring up relay $1NF$ (Fig. 2) on its left-hand winding. At the end of the Z pulse relay TZ remains held and relay TA releases.

Relay $1NF$ in operating at contacts $1nf1$ opens the operating and locking circuit for relay $1GSP$, at contacts $1nf3$ and $1nf4$ connects its outer windings across the incoming speaking conductors and at contacts $1nf5$ a number obtainable tone is connected up over common lead NTE to the centre winding of relay $1NF$ from whence it is transmitted to the calling party. Relay $1GSP$ in releasing releases $1GSR$, re-completes the GSP relay chain current and also releases relay A in the control group. Relay A in releasing initiates the release of the control group in a manner along the lines to be described later, and this group is now ready to handle a subsequent call through the group selector.

Relay $1NF$ remains held until the calling party hangs up and when he does so relay $1NF$ releases and at contacts $1nf1$ re-prepares an operating circuit for relay $1GSP$ for use when a calling party originates another call over this junction.

If the calling party dials the group selecting

digit within the allowable predetermined period after the taking into use of group GCG, on the first release of relay A an energising circuit is completed for magnet DM as follows: earth, contacts $b1$ and $c1$, left-hand low resistance winding of relay C, magnet DM to battery, the winding of relay B being short-circuited during this time, while the right-hand winding of relay C is similarly short-circuited in series with resistance YH . On the re-operation of relay A at the end of the first impulse of the received train, an energising circuit is recompleted for relay B and relay C now holds operated on both its windings in series with magnet DM which will not hold in this condition, and which thereupon releases to advance its wipers to contacts 2 or 13 according to which half of the banks is being used. An operating circuit is now completed for relay N over wiper and bank DS1, operated contacts $bb1$, bank and wiper AOS1 and operated contacts $c2$ and $b3$ to battery via resistance YF , and this relay at its contacts $n1$ completes a local locking circuit for itself. At contacts $n2$ it opens the holding circuit for relay C, and at the same time short-circuits its right-hand winding so that should there be no second pulse of the train, as will be assumed in the present instance, relay C will release after a slow release period governed by the short-circuiting of its winding and will initiate hunting for a free outlet to a succeeding group selector in a manner to be shortly described.

Relay B will have held operated during the single received dialled impulse and it may be mentioned here that the presence of the metal rectifier MRA in its initial energising circuit serves to prevent the slowing up of the magnet DM which would otherwise result from the direct connection of a comparatively low value non-inductive resistance such as YG across its winding; neither magnet DM nor relay C moreover will hold operated in series with relay B. Should there be two or more impulses in the train, relays B and C will hold operated until the end of the train in similar manner as has been described for the single impulse in question.

At the end of the digit, relay A remains operated and holds relay B, while relay C commences to release slowly, relay N remaining held over its local locking circuit. On release of relay C contacts $c4$ (Fig. 2) extend earth over operated contacts $n4$ and $b6$ and wiper DS4 which will be in position 2 or 13 when digit 1 has been dialled, whereupon the crossbar relay $1GTP$ will be operated to operate the horizontal bar associated with the first one of the ten levels of outlets. Contacts $c1$ (Fig. 3) open the impulsing circuit; while contacts $c2$ and $c3$ complete a self-interrupted driving circuit for magnet AOM or BOM according as to whether digit 1-5 or 6-0 has been dialled. In the present instance magnet AOM will be set in operation, whereupon the AOS wipers are caused to test over the twenty outlets of the selector outgoing level 1 in the following manner. On the operation of relay BB, contacts $bb2$ (Fig. 3) connect up the dual testing cut-drive relay KR via contacts of the group selector vertical hold relays $1GTH-20GTH$ to corresponding contacts 2-21 on banks AOS2 and BOS2. The associated switch wipers are in turn connected up over contacts $bb3$ and wiper bank DS³ to any one of the wipers AOS4-AOS8, BOS4-BOS8 according to the position to which switch DS has been set, i. e. in accordance with the value of the received digit. In the present

instance where digit 1 has been dialled, wipers AOS2 and BOS2 will be connected up via wiper DS3 in position 2 or 13 to wiper AOS4, the bank of which gives access to twenty succeeding selectors accessible over group selector level 1, the test lead of the first one of the twenty outlets being designated 17. When on release of relay C switch AOS steps from position 1 to position 2, the magnet driving circuit is changed over to one involving contacts of the cut drive relay KR, the circuit now being as follows: earth, low resistance winding of relay N, contacts kr2 and krr1, wiper DS2 in position 2 or 13, contacts bb5, bank and wiper AOS1, contacts c2, magnet interrupter contacts aom and magnet AOM to battery. If the first outlet on the selected level 1 is free, an idle resistance marking battery will be encountered on lead 17, this battery being extended thereon from the common equipment associated with the succeeding selector, whereupon relay KR will rapidly operate and will open the magnet driving circuit at contacts kr2 (Fig. 3). If this outlet is busy, then switch AOS will rotate its wipers until a free outlet is encountered whereupon relay KR will operate and function as described. It is also possible for the first outlet on level 1 to be free and at the same time for the first outlet on another level or levels of the same crossbar selector to be busy, in which case the first vertical internal link within the crossbar switch will already be in use and it is therefore necessary to make this outlet test as busy to the hunting switch AOS. This is done by means of the contacts 1gth2-2gth2 (Fig. 3) in the operating circuit of relay KR so that if outlet 17 were free, but if at the same time the first vertical internal link were busy, relay 1GTH would be operated and the idle marking battery would be unable to reach relay KR, since the circuit thereto would be opened at contacts 1gth2. In the next position of switch AOS, contacts 2gth2 become effective to determine whether or not the second internal link is busy and so on.

Assuming that the outlet 17 is taken in use, relay KR in operating in addition to opening the magnet driving circuit also at contacts kr2 completes an operating circuit for relay KRR and at contacts krr1 extends an earth forward over the upper low resistance winding of relay KR to guard the outlet seized.

Relay KRR in operating at contacts krr1 further disconnects the magnet driving circuit, at contacts krr2 prepares for the known dual testing function of relay KR in case two or more control groups should happen simultaneously to test on the same outgoing link, this function being described in our above-mentioned application, while contacts krr3 prepare to maintain relay KR operated independently of the crossbar vertical holding relay contacts 1gth2. Contacts krr4 (Fig. 1) extend earth up over common lead 11 to operate relay 1K, contacts krr5 and krr6 (Fig. 2) disconnect relay A from across the incoming speaking conductors, while contacts krr1 extend earth via wiper AOS3 in position 2 and lead 15 to operate the crossbar relay 1GSH and this relay in operating at its contacts 1gsh1 completes an operating circuit for the crossbar relay 1GTH. The functions of these relays 1K, 1GSH and 1GTH will be described later.

Relay A in releasing at contacts a1 (Fig. 3) short-circuits and releases relay, whereupon at contacts b5 (Fig. 1) relay BB is released, at contacts b4 relay 1GSR is released and at contacts b6 (Fig. 2) relay 1GTP is released. On release

of relay BB, contacts bb3 open the circuit of relay KR which in releasing brings down relay KRR. Furthermore, at contacts bb6 and bb1 (Fig. 3) a homing circuit is completed for switch DS via the earthed low resistance winding of relay N and wiper and bank DS1 and at contact bb5 a homing circuit is completed for switch AOS from the same earth. When both of these switches reach their home positions, the homing circuit for relay N is opened at wipers and banks DS1 and AOS1. During the homing of these switches it will be noted that contacts n3 (Fig. 1) maintain the GSP relay chain circuit open so that even when relay 1GSP is released on operation of relay 1K as will be later described, none of the relays 1GSP-10GSP can be re-operated until such time as the control group is completely restored to normal as indicated by the release of relay N. Meanwhile, in the group selector, relay 1K in operating at contacts 1k1 opens the holding circuit for relay 1GSP and this relay releases. Relays 1GSH and 1GTH in operating operate their associated vertical bars which together constitute the first vertical internal link within the crossbar unit, whereupon the sets of contacts

1GSP 1GTH
1GSH 1-3 and 1GTP 1-3

at the intersection of the vertical and horizontal bars in question are operated to extend the incoming junction through to the succeeding selector taken into use. Following the operation of relays 1GSH and 1GTH, the horizontal relays 1GSP and 1GTP are released, the former in response to the operation of relay 1K and the latter in response to the release of relay B in the control equipment, but the pins or their equivalents which are engaged by the actuated vertical bars remain held without appreciably restraining the restoration of the horizontal bars which takes place on release of relays 1GSP and 1GTP. On release of relay KRR in the control equipment, the operating circuits of relays 1K, 1GSH and 1GTH are opened, but before relay KRR is released following the release of relays A and B, BB and KR, an earth will have been returned back over the P lead (Fig. 2) from the succeeding selector in response to its seizure so that these relays will remain held throughout the setting up of the succeeding switches of the train, and then throughout the ensuing conversation.

If now another call should arrive over the junction line terminating on relay 2GSP this relay will operate and lock over its contacts 2gsp1, while at its contacts 2gsp2 and 2gsp3 the other relays of the chain are prevented from operating. When relay 2GSP and its associated relays are connected through to the common group GCG, relay A will be connected to the junction and will operate the waiting relay in the calling outgoing relay set to allow of the re-transmission of the group selecting digit as and when it is desired.

If two or more calls arrive simultaneously, the GSP relay with the lowest prefix number will in operating cut out the other GSP relay or relays involved and the other call or calls will have to wait until the control group again comes free when the process will be repeated if more than one call wishes to switch in to the control group.

In case a call arrives over a junction while the common equivalent GCG is in use, the associated relays in the group selector will be unable to connect with the common equipment and relay A will not be connected to the junction, so that on the dialling of the group selecting digit and any

succeeding digits these will be stored at the outgoing relay set until such time as the control equipment becomes free and can be taken into use when re-transmission can take place as described.

Returning now to the search for a free outlet by switch AOS, if all outlets prove to be busy, switch AOS will rotate its wipers to contacts 22 where a battery potential via resistance YJ will be encountered which feeds back over bank and wiper AOS4, bank and wiper DS3, contacts bb3 and wiper and bank AOS2 to bring up relay KR. Relay KR functions as before described with the exception of contacts krr1 (Fig. 2) which extend earth over wiper AOS3 in position 22 and then over common lead 14 to bring up relay 1NF. Relay 1NF in operating at its contacts 1nf1 disconnects the locking circuit for relay 1GSP, at contacts 1nf2 completes a local locking circuit for relay 1K which will have been operated over lead 11, at contacts 1nf3 and 1nf4 connects itself across the incoming speaking conductors and at contacts 1nf5 a busy tone source over common lead BTE is connected up via contacts 1k3 to the centre winding of relay 1NF from whence busy tone is transmitted to the calling party. During this time the common control proceeds to release in normal manner so as to be available for use in setting up further calls on the group selector.

When the calling party subsequently hangs up after receiving the busy tone, relay 1NF releases and releases relay 1K at contacts 1nf2, while at contacts 1nf1 relay 1GSP is re-connected to the incoming junction negative lead in readiness for the setting up of a further call by this subscriber.

Considering now the second method of carrying the invention into effect, reference should be had to Figs. 5 and 6.

As previously mentioned, Fig. 6 merely shows the modifications which are necessary to the incoming crossbar group selector already described to enable junction busy signalling to be carried out whenever the associated control equipment is in use, the modifications involving extra contacts 1k4, b1 and n5 on relays 1K, B and N. Contacts 1gsr2 which were previously an ordinary change-over combination are now a make-before-break changeover combination; an additional common lead 18 between the group selector and its associated equipment GCG is also provided.

When the outgoing relay set of Fig. 5 is taken into use, relay TB, which in conjunction with its non-inductive resistance shunt forms the idle marking resistance battery, is operated by earth extended forward over the P lead from the testing relay in the preceding stage. This relay in operating at its contacts tb1 disconnects the "junction busy" relay JCB from the outgoing junction positive lead and connects earth thereto.

This earth extends forward to the incoming selector of Fig. 6 and then over contacts 1k4 and 1gsr3 to common lead 18 from which lead it extends back to the positive leads of all the other incoming junctions terminating on the selector and brings about the operation of the JCB relays at the outgoing ends of these junctions. The JCB relays in operating, at their contacts jcb1 disconnect the standing idle marking batteries via the relays TB and so mark their respective outgoing relay sets as busy to the group of selector switches which have access to such junctions.

When the subscriber's loop is extended forward to the outgoing relay set, relay OA operates and at contacts oad1 brings up relay OB. Relay OB

5 in operating at contacts ob2 extends a guard earth on to the incoming P lead and at contacts ob3 operates relay JX. Relay JX in operating at contacts jx1 completes an energising circuit for the slow-to-operate relay JZ, and at contacts jx2 extends earth over contacts oa2 and the windings of relays D and I to the outgoing junction negative lead and at the distant incoming end this brings about the operation of the crossbar horizontal relay 1GSP.

When relay JZ operates after its slow period, it completes a local locking circuit for itself and opens the energising circuit for relay TB at contacts jz1, while at contacts jz2 it opens the circuit for relay JX which commences to release slowly. On release of relay JX, relays D and I remain connected via contacts oa2 and jz3 across the outgoing loop in readiness for the repetition of trains of impulses and of subsequent supervision of the progress of the call.

Meanwhile, at the distant end the operation of relay 1GSP brings about the operation of relay A in the associated common equipment on its left-hand winding and relay A in operating brings up relay B which at contacts b4 completes an operating circuit for relay 1GSR and at b7 maintains the "junction busy" earth on to common lead 18 which connects with the positive wires of the incoming junctions to the group selector. On operation of relay 1GSR contacts 1gsr1 lock relay 1GSP in a local circuit, contacts 1gsr2 connect relay A across the incoming leads and contacts 1gsr3 disconnect the earth at common lead 18 from the positive wire of this calling junction. All this takes place before relay JX at the distant end releases after having been disconnected in response to the operation of relay JZ, and hence when relays D and I are left connected across the junction at the outgoing end, relay A will already be connected thereto at the incoming end and the circuit will be ready to receive trains of impulses.

On each train of impulses relay OA at the outgoing end responds, and at its contacts oa2 repeats these out over the junction, relay OC being operated during each train to short-circuit relays D and I so as to provide an impedance-free impulse repeating loop. The operation of the incoming group selector in response to the received train of impulses is as already described.

50 When the call has been set up through the group selector GSU, the common equipment GCG is released by the operation of relay KRR therein, whereupon relays A and B release in turn and restore relay 1GSR. Relay 1GSR in restoring does not now reconnect common lead 18 to the positive line of the junction in question, since relay 1K in the group selector will have been operated, and at contacts 1k4 will open the circuit until the call is subsequently concluded. During the release of the control equipment, relay N maintains the "junction busy" earth at contacts n5 on common lead 18, but when relay N restores the earth is removed, whereupon the JCB relays at the outgoing end of all the other junctions incoming to the group selector are released and restore the idle marking batteries on to the incoming P leads of their associated outgoing impulse repeating relay sets in readiness for a further call over one of these junctions to the incoming group selector.

What we claim as new and desire to secure by Letters Patent is:

1. In a switching system having a plurality of 75 independent impulse transmitters, a plurality of

primary lines corresponding respectively to said impulse transmitters, a plurality of groups of secondary lines, a crossbar switch in which all of said lines terminate, a control unit for said switch, means controlled by a calling condition on any one of said primary lines for transmitting a signal from said control unit back over that primary line to cause the impulse transmitter corresponding thereto to begin transmitting impulses over that line to said control unit, and means in said unit controlled by said impulses for selecting a group of secondary lines in accordance with said impulses and operating said crossbar switch to connect said one primary line to a secondary line in the selected group.

2. In a switching system having a plurality of independent impulse transmitters, a plurality of primary lines corresponding respectively to said impulse transmitters, a plurality of groups of secondary lines, a crossbar switch in which all of said lines terminate, a control unit for said switch, means normally controlled by a calling condition on any one of said primary lines for transmitting a signal from said control unit back over that primary line to cause the impulse transmitter corresponding thereto to begin transmitting impulses over that line to said control unit, means in said unit controlled by said impulses for selecting a group of secondary lines in accordance with said impulses and operating said crossbar switch to connect said one primary line to a secondary line in the selected group, and means preventing said first means from transmitting signals from said control unit back over any two of said primary lines simultaneously regardless of the time relationship in which calling conditions appear on such two primary lines.

3. In a switching system having a plurality of independent impulse transmitters, a plurality of primary lines corresponding respectively to said impulse transmitters, a plurality of groups of secondary lines, a crossbar switch in which all of said lines terminate, a control unit for said switch, means normally controlled by a calling condition on any one of said primary lines for causing the impulse transmitter corresponding to that line to transmit impulses over such line to said control unit, means in said unit controlled by said impulses for selecting a group of secondary lines in accordance with said impulses and operating said crossbar switch to connect said one primary line to a secondary line in the selected group, and means preventing impulses from being transmitted to said control unit concurrently by two of said transmitters over their respectively corresponding primary lines.

4. In a switching system, a crossbar switch having a plurality of incoming lines and a plurality of outgoing lines, a control unit individual to said switch, means controlled by a calling condition on any one of said incoming lines for conditioning said unit to receive impulses over that line and for then reverting a signal over said line to initiate the transmission of impulses to said control unit, and means in said control unit for operating said crossbar switch selectively in accordance with the impulses thereafter received over said incoming line, thereby to connect said line to a selected one of said outgoing lines.

5. A switching system as claimed in claim 4, wherein each of said incoming lines has an individual storage device in which impulses are stored at times, and wherein each of said devices

transmits such stored impulses over its associated line to said control unit responsive to said signal being reverted over that line.

6. In a switching system, a crossbar switch having a plurality of incoming lines and a plurality of outgoing lines, a control unit individual to said switch, means controlled by a calling condition on any one of said incoming lines for conditioning said unit to receive impulses over that line, said means effective in the event that a calling condition appears simultaneously on two of said incoming lines to condition said unit first to receive impulses over a particular one of said two lines and, after said impulses have been received, to condition said unit to receive impulses over the other of said two lines, means operated when said control unit has been conditioned to receive impulses over any one of said incoming lines to revert a signal over such line to initiate the transmission of impulses to said unit, and means in said control unit for operating said crossbar switch selectively in accordance with the impulses over any incoming line thereby to connect such incoming line with a selected one of said outgoing lines.

7. In a switching system, a crossbar switch having a plurality of incoming lines and a plurality of outgoing lines, a control unit individual to said switch, means normally controlled by a calling condition on any one of said incoming lines for conditioning said unit to receive impulses over that line and for then reverting a signal over said line to initiate the transmission of impulses to said control unit, means in said control unit for operating said crossbar switch selectively in accordance with the impulses thereafter received over said incoming line, thereby to connect said line to a selected one of said outgoing lines, and means effective, in the event that a calling condition appears on any other incoming line while said impulses are being received over said one incoming line, to prevent said first means from reverting a signal over said other incoming line until said crossbar switch has been operated to connect said one incoming line to said selected outgoing line.

8. In a switching system, a crossbar switch having a plurality of incoming lines and a plurality of outgoing lines, a control unit individual to said switch, means normally controlled by a calling condition on any one of said incoming lines for conditioning said unit to receive impulses over that line and for then reverting a signal over said line to initiate the transmission of a group of impulses to said control unit, means in said control unit for receiving said group of impulses and operating said crossbar switch selectively in accordance therewith, thereby to connect said line to a selected one of said outgoing lines, and means effective, in the event that a calling condition appears on any other incoming line while said impulses are being received over said one incoming line, to prevent said first means from reverting a signal over said other incoming line until all the impulses of said group have been received.

9. In a switching system, a crossbar switch having a plurality of incoming lines and a plurality of groups of outgoing lines, a control unit individual to said switch, a conductor common to all of said incoming lines, means operated responsive to the seizure of any one of said incoming lines to complete a guarding circuit extending over said conductor to said control unit thereby to temporarily disable the other said incoming lines, means in said control unit operated directly over the seized incoming line to select a particu-

13

lar group of said outgoing lines, other means in said unit then operated to search for an idle outgoing line in the selected group and, when one is found, to operate said crossbar switch to connect the seized incoming line to said idle outgoing line, and means thereupon operated to render said guarding circuit ineffective, thereby consequently to enable said other incoming lines.

CHARLES GILLINGS.
LAWRENCE JOHN MURRAY.
